United States Patent Office

Des. 219,421
Patented Dec. 15, 1970

219,421

CLAMP

Alexander W. McPherson, Farmington, Mich., assignor
to Dover Corporation (De-Sta-Co Division), a corpora-
tion of Delaware

Filed June 18, 1969, Ser. No. 17,766

Term of patent 14 years

Int. Cl. D8—03

U.S. Cl. D8—72

FIG. 1

FIG. 2

FIG. 3

FIG. 4

FIG. 5

FIG. 1 is a perspective view of a clamp showing my new design;

FIG. 2 is a side elevation of the clamp;

FIG. 3 is a top elevation of the same clamp;

FIGS. 4 and 5 are end elevations of the same clamp.

I claim:

The ornamental design for a clamp, as shown and described.
